[57] CLAIM

The ornamental design for a roof panel for automotive vehicles, substantially as shown.

DESCRIPTION

FIG. 1 is a top plan view of a roof panel for automotive vehicles showing my new design;
FIG. 2 is a rear end elevational view thereof;
FIG. 3 is a bottom plan view thereof;
FIG. 4 is a front end elevational view thereof;
FIG. 5 is a side elevational view thereof, the opposite side being substantially a mirror image of the side shown herein; and
FIG. 6 is an enlarged fragmentary sectional view thereof taken along line 6—6 of FIG. 1.

FIG. 1

FIG. 2

FIG. 3

FIG. 4

FIG. 5

FIG. 6
